CLAIM

The ornamental design for a floor tile, as shown and described.

DESCRIPTION

FIG. 1 is a right-side, top perspective view of a floor tile showing my new design according to one embodiment.

FIG. 2 is a front view of my new design shown in FIG. 1.

FIG. 3 is a rear view of my new design shown in FIG. 1.

FIG. 4 is a right-side view of my new design shown in FIG. 1.

FIG. 5 is a left-side view of my new design shown in FIG. 1.

FIG. 6 is a top view of my new design shown in FIG. 1.

FIG. 7 is a bottom view of my new design shown in FIG. 1.

FIG. 8 is a cross-sectional view of my new design shown in FIG. 1 along line 8-8.

FIG. 9 is a right-side, top perspective view of my new design shown in FIG. 1 coupled to three other floor tiles; and, FIG. 10 is a front view of a floor tile showing my new design according to another embodiment.

The broken lines in the drawings depict environment that forms no part of the claimed design.

1 Claim, 8 Drawing Sheets
